UNITED STATES PATENT OFFICE.

VICTOR W. ZILEN, OF CHATTANOOGA, TENNESSEE, ASSIGNOR TO LUCEY MANUFACTURING CORPORATION, OF CHATTANOOGA, TENNESSEE, A CORPORATION OF TENNESSEE.

CROWN BLOCK CABLE GUARD.

1,423,550.

Specification of Letters Patent. Patented July 25, 1922.

Application filed September 13, 1921. Serial No. 500,465.

To all whom it may concern:

Be it known that I, VICTOR W. ZILEN, a citizen of the United States, residing at Chattanooga, in the county of Hamilton and 5 State of Tennessee, have invented certain new and useful Improvements in Crown Block Cable Guards; and I do hereby declare the following to be a full, clear, and exact description of the same, reference being had to the accompanying drawings, 10 forming part of this specification.

This invention relates to crown blocks of drilling rigs and is especially applicable to guards adapted for use in connection with 15 the sheaves or pulleys carried on the crown block.

As is well known, very heavy loads are suspended from the sheaves on the crown block of well drilling rigs and under certain 20 conditions such, for instance, as a sudden variation of the load from maximum to zero, the cable by which the load is suspended from the sheaves will jump out of the grooves in the sheaves. An object of 25 the present invention is to meet this condition and insure the safety of the operator by providing the crown block with guards for each of the sheaves that will effectually prevent the displacement of the cable from the 30 sheaves.

In the accompanying drawings.—

Figure 1 is a top plan view of a crown block embodying the present improvements, all except one or two of the guards being 35 shown partly in section;

Fig. 2 is a side elevation, partly in section, of the crown block and cable guards; and

Fig. 3 is a sectional view on the line 3—3, 40 Fig. 1.

Practically all crown blocks now in use consist generally of a plurality of spaced frame members having the various sheaves or pulleys, such as the drilling line, sand 45 line and casing line sheaves, mounted thereon between the frame members and while the present invention is applicable to any form of crown block, a block and pulleys such as those described in U. S. Patent No. 50 1,368,775, dated February 15, 1921, have been selected for purposes of illustration in the present case and a brief description of the essential parts thereof will suffice.

The crown block consists of five frame 55 members 10 preferably formed of metal I-

beams, two of said frame members being somewhat longer than, and extending at one end beyond, the others to receive the sand line sheave 11. Frame members 10 are spaced apart from each other by spacer 60 frames 14, preferably of the type described in the above mentioned patent, and said frame members are provided on the upper surfaces with suitable bearings for the shafts 15 of the sand line sheave 11, the casing 65 sheaves 12 and the drilling line sheave 13, each of said sheaves being positioned on its respective shaft in the spaces intermediate adjacent members 10 of the block. Further detailed description of the frame members 70 of the crown block, or of the sheaves and shafts, is deemed unnecessary here for an understanding of this invention, although a full disclosure and description of these parts will be found in the patent before referred 75 to.

In oil well rigging a cable from a hoisting apparatus is passed over the sheaves of the crown block and under sheaves of a vertically traveling block (not shown) below 80 the crown block and the load is suspended from a hoisting hook on the traveling block, the load being transmitted from the traveling block to the crown block by the cables and from the crown block, which is on the 85 top of the derrick, to the frame members of the derrick. Normally, the crown block is subjected to substantially vertical strains only, but under various operating conditions, such as a sudden variation of the load, the 90 elasticity of the derrick, the crown block framing and the cable distort the vertical transmission of strains to such a degree as to cause the cable to jump out of the groove in the crown block sheaves. To prevent this 95 accidental displacement of the cables, due to this and other causes, cable guards are provided on the crown block for each of the sheaves.

In the preferred embodiment of the invention the guards 16 are comparatively narrow, being a trifle wider than the sheaves, and are of arcuate formation, conforming to the contour of that portion of the sheaves above the frame members 10. Two guards 105 are provided for each sheave, one on each side of the sheave, practically the entire periphery of the sheave above the frame members being enclosed by the two guards. Each guard is provided with a base 17 ex- 110

tending laterally on each side of the guard and of sufficient length to straddle or bridge the space between two adjacent frame members 10, the opposite ends of base 17 resting 5 on the top of the frame members with the guard 16 positioned intermediate the frame members and in proximity to the grooved periphery of the sheave.

For securing the guard on the crown 10 block a clamping plate 18 of sufficient length to bridge the space between the frame members is positioned beneath the guard base 17 in engagement with the bottom surfaces of the flanges to the I-beams. A pair of bolts 15 19 extend through the plate and guard base with the heads of the bolts seated in recesses 20 in the plate 18 to prevent rotation of the bolts, and the plate and guard are secured or clamped on the crown block frame 20 members by nuts threaded on the upper ends of bolts 19, the bolts being preferably arranged with their threaded ends projecting above the crown block to render them accessible.

25 As will be obvious the guards can be adjusted towards and away from a sheave,—that is, longitudinally of the frame members 10,—by loosening the bolts 19 and to permit adjustment of the guard transversely of the members 10 and a sheave, the guard base 17 is provided on opposite sides of the guard with elongated slots 21. The bolts 19 extend through said slots and by loosening the bolts the guard can be adjusted transversely, the 30 base 17 being made sufficiently long to maintain its bearing on both of the frame members 10 in any of the locations to which it might be moved.

Furthermore, by mounting the guards on 40 the frame members instead of on the sheaves or on the shafts of the sheaves the guards can easily be removed without disturbing the sheaves. This is very advantageous particularly when there is a load imposed on the sheave, because under these conditions it would be rather troublesome to remove the sheave or sheave shaft if the guard was mounted on either of these members instead of on the frame.

50 What is claimed is:

1. In a crown block, the combination of spaced frame members, sheaves journaled on the frame members and positioned in said spaces, guards for each of said sheaves, 55 said guards being movable toward and away from their respective sheaves to vary the distance between the sheaves and their respective guards.

2. In a crown block, the combination of 60 spaced frame members, sheaves journaled

on the frame members and positioned in said spaces, and guards for each of said sheaves, said guards being adjustably mounted on the frame members and said guards being removable from said frame independently of the sheaves and sheave 65 mountings.

3. In a crown block, the combination of spaced frame members, sheaves journaled on the frame members and positioned in 70 said spaces, guards for each of said sheaves, said guards being movable towards and away from the sheaves and transversely of the sheaves, and means for locking said guards in adjusted position.

4. In a crown block, the combination of spaced frame members having lateral flanges, sheaves journaled on said members and positioned in said spaces, guards for each of said sheaves, each of said guards having a 80 base adapted to bridge the space between adjacent frame members and rest on the upper surfaces of the flanges of said members, a clamping plate for each guard adapted to bridge the space between adjacent frame 85 members and seat against the under surfaces of said flanges, and securing means extending through said plate and guard base.

5. In a crown block, the combination of spaced frame members having lateral flanges, 90 sheaves journaled on said members and positioned in said spaces, guards for each of said sheaves, each of said guards having a slotted base adapted to bridge the spaces between adjacent frame members and rest on the flanges of said members, a clamping plate for each guard adapted to seat against the bottom surface of said flanges below the guard base, and releasable locking elements extending through said plates and slots in 100 the base of each guard.

6. A rope guard for crown block sheaves comprising a base extending on opposite sides of the guard, there being an elongated slot in the base on each side of said guard, 105 a clamping plate, and securing elements extending through the plate and the slots in the guard base.

7. In a crown block, the combination of the sheave support, a sheave guard, a guard base extending on opposite sides of the guard and adapted to engage the sheave support, there being an elongated slot in the base on each side of the guard, a clamping plate adapted to engage the sheave support beneath the guard base, and means extending through the plate and the slots in the base for securing the guard on the sheave support.

VICTOR W. ZILEN.
